* cited by examiner

Primary Examiner—Carol Rademaker(74) *Attorney, Agent, or Firm*—Venable LLP; James R. Burdett; Jeffri A. Kaminski(57) **CLAIM**

The ornamental design for a six-sided container, as shown and described.

DESCRIPTION

FIG. 1 is a top, front perspective view of the six-sided container showing my design;

FIG. 2 is a front elevation view thereof, the rear elevation view being identical;

FIG. 3 is a right side elevation view thereof, the left side elevation view being identical;

FIG. 4 is a top plan view thereof;

FIG. 5 is a bottom plan view thereof; and,

FIG. 6 is a planar cross-section view thereof, taken at the point of section line 6—6 in FIG. 3.

All side views of the six-sided container are identical.

The broken lines shown in FIG. 5 are for environmental purposes only and form no part of the claimed design.
